SECURE FASTENING MEANS

Sverre Quisling, Madison, Wis.

Application October 17, 1933, Serial No. 693,994

4 Claims. (Cl. 292—137)

This invention relates to improvements in secure fastening or locking means for connecting together the free edges of adjacent rigid members.

5 The object of this is to provide fastening means for closures which shall be simple in operation and positive in action.

A further object of the invention is a provision of locking means which will be proof against 10 accidental opening when once closed.

A further object is to provide a closure which shall be substantially air tight.

Altho a preferred embodiment of the invention is herein shown and described, it is understood 15 that changes may be made within the scope of what is claimed.

In the drawings:

Figure 1 is a side elevation of a device constructed in accordance with the invention and 20 applied to a hand bag, parts being shown in section;

Figure 2 is an end view of the device in open position;

Figure 3 is a section on the line 3—3 of 25 Figure 1;

Figure 4 is a section on the line 4—4 of Figure 1;

Figure 5 is a section showing the members of locking means disengaged;

30 Figure 6 shows a modified form of bag closure;

Figure 7 is a vertical section showing a closure applied to a cylindrical metal container; and,

Figure 8 is a horizontal section on the line 8—8 of Figure 7.

35 Referring to the drawings in detail, the present embodiment of the invention is shown to comprise a substantially tubular, rigid closure member 1, and its companion rigid member of semicircular cross section 2, hinged together at their lower

40 ends as at 3. The member 1, altho substantially circular in cross section is pressed inwardly to less diameter for half of its circumference forming a seat 4 and shoulders 5 against which its companion member 2 rests when the closure is shut.

45 By forming this seat, the closure when locked shut has a cylindrical shape with no protruding or rough edges which might hang into or tear the clothing of the user.

50 At several points throughout its length, the member 1 is cut away for half of its circumference upon the side facing its companion member 2, as at 6.

55 Formed on the companion member, at points opposite to the cut out portions 6 of the main

member, are curved fingers 7, so shaped as to fit the inside curvature of the member 1.

The member 1 and its companion member 2 have depending flanges 8 and 9 to which are secured the open ends of a hand bag 10.

5 Threaded through the member 1, is a coacting sliding piece or cord 11 which is brought out through an opening at the top to form a loop, threaded back through the other side of the member, down through the bag and out at the bottom to form a second loop. This sliding piece or cord has along its length certain distances of increased thickness as at 12 and decreased thickness as at 13.

The fingers 7, of the member 2, are at their 15 outer ends, spaced apart at a distance slightly greater than the lesser diameter 13 of the sliding piece or cord but much less than the greater diameter of 12. When the closure members are brought together, the fingers 7, extending 20 through the cut out portions 6 of the member 1, will pass over the smaller diameter of the sliding piece or cord 11. When the loop at the top of the bag is pulled, the greater diameter 12 of said cord 11 will slide between the fingers 7, 25 pulling the two members of the closure more tightly together and securely locking them in place. A pull upon the loop at the bottom of the bag will draw the lesser diameter of the cord 13 between the fingers, and the closure is released 30 and may be easily opened. Enlarged portions 14, 35 may be provided on the cord outside of the bag so that the cord may not be accidentally pulled completely within the bag or a ring may be fastened at this point. The loop or ring at the top of the bag may serve as a handle which will prevent the bag being opened either accidentally or by a thief without the knowledge of the carrier.

A slightly modified form is shown in Figure 40 6. The same closure is used except for shape, but the sliding member or cord extends in a longer loop outside of the bag, thereby forming a longer handle by which the bag may be carried.

45 The sliding segment or cord in this form has a relatively small portion of its length enlarged. By the adoption of this type sliding segment, a pull in either direction will release the closure.

In Figures 7 and 8 the closure is shown applied to a cylindrical metal container. In this 50 form, the main member 1 is secured to the body of a container 15, while its companion member 2 is secured to a top or cap 16. The same closure means is used as before in conjunction with the type sliding segment shown in Figure 6. In both 55

these forms the sliding segment or cord has a relatively short portion of its length enlarged which in the illustration is accomplished by clamping a metal sleeve upon a cord. Rings or other devices may be attached to the ends of said member in order to facilitate locking and unlocking of the cover of a can. Of course, the segment may be made entirely of metal having out turned finger piece 17 passing through a slot 18 in the side of the main member 1 as in Figure 8 for the purpose of moving relative position of said sliding piece.

Having thus described my invention what I claim is:—

- 15 1. In a device of the character described, a main member and a companion member, the main member being tubular in shape and having cut out portions and the companion member carrying arch shaped fingers adapted for engagement with said cut out portions, a sliding segment of varying diameter threaded through the main member so that main and companion members are locked together and unlocked upon relative longitudinal movement of said sliding segment.
- 20 2. Means for connecting the free edges of two adjacent separable rigid members, the first member being of hollow construction with keeper opening means cut in its side, said member containing incased therein a slidable elongated segment having a portion of its length of small diameter and a portion of larger diameter, the second opposed member having arc shaped projecting means extending into the cutout keeper opening means in the first member, whereby said two opposed members are fastened together when the larger diameter of the elongated member in

the first segment is drawn inside the arch of said projecting means of the second member, and are separable when the small diameter replaces it.

3. In a device of the character described two separable rigid opposed members, arch shaped fingers extending from the first member, a wall on the second member having keeper openings for receiving said arch shaped fingers, an elongated segment slideable within the wall of the second member and having a portion thereof of enlarged cross section so as to latch the first and second members together when the portion of enlarged cross section is made to slide between the arch shaped fingers of the first members when projecting into the keeper openings in the second member and so as to unlatch said opposing members when the portion of smaller cross section replaces it.

4. In a device of the character described, two separable rigid opposed members, the first of said members having a passageway therethru containing an elongated slideable segment of large and smaller cross section with cut out keeper openings in the wall of said passageway, the second member having projections adapted to pass thru the openings of the first member and engage the larger cross section of the elongated segment to hold the first and second members together and also to permit the passage of the smaller cross section of said elongated segment when positioned between said projections of the second member to allow for separation of said opposed first and second members, the elongated segment in the first member being adapted to be easily positioned for that purpose.

SVERRE QUISLING.
